[57] **CLAIM**

The ornamental design for a furniture unit with wash basin, mirror, lateral cupboard and suspended drawers, as shown and described.

DESCRIPTION

FIG. 1 is a front elevational view of a furniture unit with wash basin, mirror, lateral cupboard and suspended drawers showing my new design;

FIG. 2 is a left side perspective view thereof;

FIG. 3 is a fragmentary view showing the lower portion of the pedestal supporting the wash basin in an open condition;

FIG. 4 is a right side elevational view of FIG. 1;

FIG. 5 is a left side elevational view thereof;

FIG. 6 is a top plan view thereof; and,

FIG. 7 is a bottom plan view thereof.

FIG. 1

FIG.2

FIG.3

FIG. 4

FIG. 5
